UNITED STATES PATENT OFFICE.

GURDON H. WILLIAMS, OF CLEVELAND, OHIO.

CLAM-SHELL BUCKET.

No. 823,015.

Specification of Letters Patent.

Patented June 12, 1906.

Application filed March 31, 1905. Serial No. 253,026.

To all whom it may concern:

Be it known that I, GURDON H. WILLIAMS, a citizen of the United States, and a resident of Cleveland, county of Cuyahoga, and State of Ohio, have invented a new and useful Improvement in Clam-Shell Buckets, of which the following is a specification, the principle of the invention being herein explained and the best mode in which I have contemplated applying that principle, so as to distinguish it from other inventions.

My invention relates to an improved clam-shell bucket, and particularly to a device of this character in which the power for opening and closing the bucket is generated upon or in the near vicinity of the bucket itself. The advantage of such a bucket and the means embodied therein are hereinafter fully described and such means particularly pointed out in the claims.

The annexed drawings and the following description set forth in detail certain mechanism embodying the invention, such disclosed means constituting but one of various mechanical forms in which the principle of the invention may be used.

In said annexed drawings, Figure 1 represents a side elevation of my improved clam-shell bucket with the scoop members closed. Fig. 2 represents an end elevation. Fig. 3 represents a side elevation with the scoop members open. Fig. 4 represents a plan view, and Fig. 5 represents a broken enlarged side elevation, of a part of the operating mechanism.

My invention embodies the use of a motor as a substitute for cables which have heretofore been generally used for opening and closing the scoop members of clam-shell buckets. A motor may be thus used in connection with any of the present forms of buckets; but I shall describe its use herein particularly with reference to an improved operating mechanism designed to be an improvement upon the mechanism shown, described, and claimed in United States Letters Patent No. 779,512, granted to me January 10, 1905.

It is well known that when cables are used to open and close the scoop members it is necessary to greatly multiply the power closing force and also to make the weight of the bucket excessive in order to completely fill the bucket during the closing operation, and thus render the mechanism efficient. This is occasioned by the fact that the pull upon the cables is necessarily exerted at a long distance from and above the bucket

itself, so that if the resistance between the scoop members is greater than the force derived from the closing mechanism the bucket is lifted upwardly without being completely filled, unless the weight of the bucket is greatly in excess of that which it is otherwise necessary to have. This resistance between the scoop members varies greatly at different times, depending upon the character of the work that is being done, so that in order to be prepared to overcome the greatest possible resistance the power closing mechanism is necessarily made very strong and the bucket very heavy.

By the use of a motor the greater part of the power closing multiples and much of the weight of the bucket are eliminated by reason of the fact that the power to open or close the scoop members is generated upon or near the bucket itself by reason of having the motor mounted upon the frame of the bucket and connected to the operating mechanism so that the bucket is not lifted upwardly when the resistance to the closing of its scoop members is increased beyond the power of the closing mechanism; but, on the other hand, the bucket will lie with its entire weight upon the material being operated upon. Further, by the use of a motor the operating mechanism of the bucket is greatly simplified, due to the elimination of power-wheels, cables, pulleys, &c.

Centrally journaled in a frame A is a driving-shaft B, having secured to its respective outer projecting ends two driving-pinions b b, Fig. 4. Mounted in the frame A upon opposite sides of the center plane of the frame passing through the axis of the shaft B are two rocking shafts C C, respectively parallel with shaft B. Upon the projecting ends of these rock-shafts are mounted two pairs of oppositely-disposed oscillatory sectors C' C' and C'' C'', respectively. The members of each pair of sectors mesh with each other, and one of such members is engaged by a driving-pinion b, so that the rotation of this pinion will cause the members of the pairs of sectors to rock in opposite directions. Two scoop members E E are provided, as shown, one on each side of the central plane of the frame. Upon the front and rear of the frame and near the top thereof on both sides of the central plane of the frame are pivoted links D D, whose other ends are pivoted to the front end of the scoop member E upon the same side. Forming a continuation of the sectors

C' and C^2 , as plainly shown in Fig. 5, are arms or links C^3 , whose outer ends are connected to shafts C^4 C^5 , respectively journaled in the rear ends of the scoop members E E . It will be noted from Fig. 1 that the shafts C C , which contain the axes of oscillation of the sectors C' C^2 , lie within the vertical plane containing the pivotal axes of the upper ends of the links D , or, in other words, the shafts C are at a distance less removed from the center plane of the frame than the pivotal axes of the upper ends of said links D . The advantages of this construction will be hereinafter pointed out.

15 Suitably keyed to the central driving-shaft B intermediately of the pinions b is a main gear F . A motor H^6 , Fig. 2, is provided with a suitable motor-frame H , mounted in the frame A by means of the downwardly-projecting arms h h , in which the central shaft B has bearings, and the transverse shaft H' , supporting the integral arms h' h' , as plainly shown in Fig. 4. The motor-shaft is designated by H^2 and is provided with suitable bearings in said frame. Said motor-shaft carries at one end a bevel-pinion H^3 , meshing with the bevel-gear H^4 , keyed to the transverse shaft H' . Carried upon the latter so as to gear with the main gear F is a pinion H^5 . The motor H^6 is provided with a suitable automatic brake, (not shown,) so that it will not run in a reverse direction when the bucket is filled or is empty, and also with friction devices (not shown) tending to cause it to disengage when overloaded.

Mounted upon the top of the bucket is a suitable sheave J , which may receive a suitable hoisting-cable adapted to elevate the bucket when it is filled. The teeth of the sectors C' C^2 , the pinions b , main gear F , and pinion H^5 are cast in between suitable shroudings, as plainly shown in Fig. 5, in order to increase their strength, as will be readily understood. The spaces between the teeth of the sectors C' C^2 and the main gear F enable ore or other material to pass between the teeth, and thus prevent them from clogging up. Various forms of motors may be utilized in my invention; but I prefer to use an electric motor because of the flexible connections that it affords in distinction to the rigid connections of a pneumatic or hydraulic motor.

55 My improved bucket is operated as follows: Assuming the bucket to be closed, as illustrated in Fig. 1, the front end of the scoop members will fall by gravity until the links D assume the vertical position, the rear end of the scoop members meanwhile being lifted. This action is due to the relative locations of the shafts C C and the upper ends of the links D D , as pointed out above. The contents of the bucket can thus be discharged with the expenditure of a very small amount

of force. The motor now being operated, the complete opening operation can be accomplished, as desired, through the bevel-gears H^3 H^4 , pinion H^5 , main gear F , pinions b , sectors C' C^2 , and arms C^3 .

It is obvious that my improved bucket-closing mechanism can be utilized upon a cable-operated bucket in addition to its use upon one which is motor-operated, if suitable power-wheels, cables, and sheaves be provided therefor.

Having described my invention in detail, that which I particularly point out and distinctly claim is—

1. In a clam-shell bucket, the combination of a frame; a motor mounted thereon; scoop members; and means supporting and moving the latter to open and close and including oscillatory members mounted upon said frame and adapted to be actuated by said motor.

2. In a clam-shell bucket, the combination of a frame; a motor mounted thereon; scoop members; oscillatory members mounted upon said frame, adapted to be actuated by said motor, and connected to one end of said scoop members; and links connected to said frame and to the other end of said scoop members.

3. In a clam-shell bucket, the combination of a frame; a motor mounted thereon; two scoop members; operating mechanism for the latter adapted to be actuated by said motor and connected to the outer ends of said scoop members; and links pivoted to said frame and to the inner ends of said scoop members, respectively.

4. In a clam-shell bucket, the combination of a frame; a motor mounted thereon; two scoop members; operating mechanism for the latter adapted to be actuated by said motor and comprising a pair of opposed sectors having gear connections with the latter and arms connecting said sectors and the outer ends of said scoop members, respectively; and links pivoted to said frame and to the inner ends of said scoop members, respectively.

5. In a clam-shell bucket, the combination of a frame; a motor mounted thereon; two scoop members; a pair of opposed sectors oscillatorily mounted upon said frame; connections between said sectors and said motor; links pivoted to said frame and to the inner ends of said scoop members, respectively; and arms connecting said sectors with the outer ends of said scoop members, respectively.

6. In a clam-shell bucket, the combination of a frame; a motor mounted thereon; two scoop members; a pair of opposed sectors; connections between the latter and said motor; links pivoted to said frame and to the inner ends of said scoop members, respectively; and arms connecting said sectors with the outer ends of said scoop members, respectively, said arms being connected to said sec-

ors at points a less distance removed from the center line of the frame than the points at which said links are pivoted to the frame.

7. In a clam-shell bucket, the combination of a frame, a motor mounted thereon; two scoop members upon opposite sides of the center plane of the frame; a pair of opposed sectors mounted upon said frame upon opposite sides thereof; connections between said sectors and said motor; links pivoted to said frame and to the inner ends of said scoop members, respectively, upon the same side; and arms connecting said sectors with the outer ends of said scoop members, respectively, upon the same side.

8. In a clam-shell bucket, the combination of a frame; a motor mounted thereon; two scoop members upon opposite sides of the center plane of the frame; a pair of opposed sectors mounted upon said frame upon opposite sides thereof; connections between said sectors and said motor; links pivoted to said frame and to the inner ends of said scoop members, respectively, upon the same side; and arms connecting said sectors with the outer ends of said scoop members, respectively, upon the same side; frame than the points at which said links are pivoted to the frame.

9. In a clam-shell bucket, the combination of a frame; two sectors mounted upon said

frame upon opposite sides of the center plane of the latter; operating mechanism connected to said sectors; a pair of scoop members upon opposite sides of said plane; links pivoted to said frame and to the inner ends of said scoop members, respectively, upon the same side; and arms connecting said sectors and the outer ends of said scoop members, respectively, upon the same side, said arms being connected to said sectors at points a less distance removed from the center line of the frame than the points at which said links are pivoted to the frame.

10. In a clam-shell bucket, the combination of a frame; a pair of scoop members upon opposite sides of the center line of said frame; links pivoted to said frame and to the inner ends of said scoop members, respectively, upon the same side; a pair of oscillatory members pivoted to said frame and connected to the outer ends of said scoop members, respectively, upon the same side, the pivotal points of said oscillatory members upon said frame being at a distance less removed from the center line of the frame than the pivotal points of said links upon the frame; and a motor mounted upon the frame and adapted to operate said oscillatory members.

Signed by me this 15th day of March, 1905.
GURDON H. WILLIAMS.
